UNITED STATES PATENT OFFICE.

MATEJ KRATKY, OF HEMINGFORD, NEBRASKA.

DESIGN FOR A FOLLOWER FOR CULINARY VESSELS.

SPECIFICATION forming part of Design No. 24,481, dated July 16, 1895.

Application filed June 20, 1895. Serial No. 553,472. Term of patent 14 years.

To all whom it may concern:

Be it known that I, MATEJ KRATKY, of Hemingford, in the county of Boxbutte and State of Nebraska, have invented and produced a new and original Design for an Internal Cover or Follower for Culinary Vessels, of which the following is a full, clear, and exact description.

Reference is to be had to the accompanying drawings, forming a part of this specification, in which—

Figure 1 is an edge view of a cover embodying my new design, and Fig. 2 is a plan view thereof.

15 The leading feature of my design consists

in the cover, round in general contour, the edge being beveled downward and outward and said edge having elongated recesses, the edge thus presenting alternate recesses *a* and elongated projecting portions *b*. A minor feature is the knob-like figure *c* in the center of the cover. 20

I claim—

The design for an internal cover or follower, herein shown and described.

MATEJ KRATKY.
